UNITED STATES PATENT OFFICE

CHARLES T. JAMES, OF LOS ANGELES, CALIFORNIA

REMOTE-CONTROLLED DRAWER

Application filed October 1, 1929. Serial No. 396,592.

This invention relates to a remote controlled drawer and has for its primary object the provision of a mechanism by which a number of different drawers at various places may be simultaneously closed and locked, or locked if already closed, by operating a switch which may be located remote from some or all of the drawers. Other objects include the provision of such a mechanism which will not interfere with the unlocking or locking and opening or closing of any or all of the drawers in the usual manner and one which will be simple, strong and reliable.

15 These objects together with other objects and corresponding accomplishments are obtained by means of the embodiment of my invention illustrated in the accompanying drawing in which:

20 Fig. 1 is a cross section through a counter having the usual type of drawer secured to its underside and fitted with my closing mechanism; Figs. 2 and 3 are sections as seen on correspondingly numbered lines of 25 Fig. 1; Fig. 4 is a fragmentary view similar to Fig. 1 but showing the drawer in open position, and Fig. 5 is a diagrammatic view showing operating switches connected to a plurality of drawer closing mechanisms.

30 As illustrative of the invention, I have shown the drawer embodied in a cabinet or counter, although it may be located in various other places. Referring with more particularity to the drawings 9 generally indicates a cabinet or closed compartment, the top 10 of which may be a portion of a counter. Slidably supported in any desired manner on the side walls 11 of the compartment is a conventional drawer 12. Attached to the

35 underside of the drawer is a rack 14 and a keeper 15; these will be more fully described later. Secured to the underside of counter 10 near the outside end of the drawer is a stop member 16 and dogs 17 to coat therewith are secured to the sides of the drawer. Each of these comprises a toothed member 17^a pivotally mounted on the side of the drawer and urged upwardly by a compression spring 17^c against a stop 17^b fixed to

40 the side of the drawer. The dogs normally

limit the outward movement of the drawer by engaging stop 16, but when it is desired to pull the drawer farther out they may be manually depressed against the springs so as to ride under the stop. The inclined surface on the back of the toothed member will enable it to be forced down under the stop when the drawer is pushed in, permitting the drawer to be closed readily.

45 Secured to the front wall of the compartment is a spring lock 19, which may be actuated by inserting a key 20 therein. The lock is mounted so that the bolt 21 is projectable downwardly, and is of conventional form except for having a tail or extension 22 secured to the upper end of the bolt. A link 23 is pivoted to this extension and supports at its upper end a latch member 24 pivoted in a protective casing secured to the front wall of the compartment. The latch member 24 has an upwardly projecting tooth 24^a and a counterweight arm 24^b. The arrangement is so balanced that the counterweight normally urges the latch upwardly where it may engage keeper 15, the movement of the counterweight arm being limited by link 23. When the bolt is retracted by turning key 20, link 23 raises the counterweight arm and lowers 24^a out of the way of keeper 15.

50 Extension 22 which is preferably of metal and an electric conductor and has a projection 22^a on one side with a piece of insulating material 25 secured in its upper portion. Adjacent thereto and suitably supported on the front of the compartment, as in a bakelite block are spring fingers 26^a and 26^b forming members of an auxiliary electric switch 26 for controlling a motor, to be described later. When the bolt is down (Fig. 2), finger 26^a is in contact with the insulation 25 and no current can flow. When the bolt is raised and the drawer is unlocked, both fingers are in contact with the metal portion of extension 22^a so that current can flow between them in effect closing the switch.

55 A shaft 28 extending transversely of compartment 9 is rotatably mounted in bearings 29 and has a worm wheel 30 secured to it. A worm 31 engages this worm wheel and is mounted on a shaft driven by

5 drawer unlocking position, said restraining means being connected to said trip lever and arranged to release said bolt, and an auxiliary switch operated by said lock and arranged to interrupt the circuit between said motor and the source of current when said bolt is in drawer locking position.

10 4. A closing mechanism for a drawer comprising an electric circuit including a motor, a control switch for connecting said motor with a source of current, a freely journaled segmental gear, a one-way drive means for connecting said motor to said gear so as to drive the latter, a drawer slidably mounted adjacent said gear and having a rack secured to it arranged to be engaged by said gear upon rotation thereof, outward travel limiting means secured to said drawer, an overbalance arm attached to said gear, a trip lever arranged to be actuated by said arm upon rotation of said gear, a spring lock having a bolt normally tending to lock said drawer in closed position, a restraining rod disposed to hold said bolt in drawer unlocking position, said rod being connected to said trip lever and arranged to be moved to release said bolt, and an auxiliary switch operated by said lock and arranged to interrupt the circuit between said motor and the source of current when said bolt is in drawer locking position.

15 5. A closing mechanism for a drawer comprising a motor and a source of current, a control switch for connecting said motor with said source of current, a shaft and overbalanced segmental gear rotatably mounted on said shaft, said shaft being arranged to be driven by said motor, means secured to said shaft adapted to engage said gear and cause said gear to be rotated with said shaft, a trip actuating arm attached to said gear, a drawer slidably mounted adjacent said gear and having a rack secured to it arranged to be engaged by said gear upon rotation thereof, a spring lock having a bolt normally tending to lock said drawer in closed position, restraining mechanism for holding said bolt in drawer unlocking position, said restraining mechanism being operated by said arm, and arranged to release said bolt, an auxiliary switch operated by said lock and arranged to interrupt the circuit between said motor and source of current when said bolt is in drawer locking position.

20 6. A closing mechanism for a drawer comprising a motor and a source of current, a control switch for connecting said motor with said source of current, a shaft, an overbalanced segmental gear rotatably mounted on said shaft, said shaft being arranged to be driven by said motor, means secured to said shaft adapted to engage said gear and cause said gear to be rotated with said shaft, a trip actuating arm attached to said gear, a drawer slidably mounted adjacent said gear and having a rack secured to it arranged to be en-

25 gaged by said gear upon rotation thereof, a trip lever arranged to be actuated by said arm upon rotation of said gear, a lock having a bolt normally tending to lock said drawer in closed position, restraining means for said bolt to hold the latter in drawer unlocking position, said restraining means being connected to said trip lever, and arranged to be released to said bolt, an auxiliary switch operated by said lock and arranged to interrupt the circuit between said motor and the source of current when the bolt is in locked position.

30 7. A closing mechanism for a drawer comprising a motor and a source of current, a master control switch for connecting said motor with said source of current, a segmental gear rotatably mounted on said shaft, said shaft being arranged to be driven by said motor, means secured to said shaft adapted to engage said gear and cause said gear to be rotated with said shaft, an overbalance arm attached to said gear whereby to cause the gear to revolve on said shaft to a predetermined point, a drawer slidably mounted adjacent said gear and having a rack secured to it arranged to be engaged by said gear upon rotation thereof, a trip lever arranged to be actuated by said arm upon rotation of said gear, a spring lock having a bolt normally tending to lock said drawer in closed position, a restraining rod disposed to hold said bolt in drawer unlocking position, said rod being connected to said trip lever and arranged to be moved to release said bolt, and an auxiliary switch operated by said lock and arranged to interrupt the circuit between said motor and the source of current when the bolt is in drawer locking position.

35 In witness that I claim the foregoing I have hereunto subscribed my name this 25th day of September, 1929.

40 CHARLES T. JAMES.
